UNITED STATES PATENT OFFICE.

WILLIAM L. CUMMER, OF HAMILTON, ONTARIO, CANADA.

CLOTHES-DRIER.

986,804.

Specification of Letters Patent. Patented Mar. 14, 1911.

Application filed November 19, 1909. Serial No. 528,896.

To all whom it may concern:

Be it known that I, WILLIAM L. CUMMER, of the city of Hamilton, in the Province of Ontario, Canada, have invented certain new and useful Improvements in Clothes-Driers, of which the following is a specification.

This invention relates to clothes driers of the type in which a series of folding arms supporting clothes lines are rotatably supported on a suitable standard.

My object is to devise a clothes drier of this type which can be folded and expanded with a minimum of trouble and which when folded or expanded is secure against accidental displacement. I attain my object by a construction which is shown in the accompanying drawings in which—

Figure 1 is a side elevation of a clothes drier, constructed in accordance with my invention, in its expanded position. Fig. 2 is a similar view showing the drier in its folded position. Fig. 3 is an enlarged sectional detail of the top of the post and the guide cap. Fig. 4 is a plan view of a guide cap. Fig. 5 is an enlarged vertical section of the joint between the two parts of the post.

In the drawings like letters of reference indicate corresponding parts in the different figures.

The drier is provided with a post formed in two parts A and B. The lower part of the post is adapted to fit within a socket C permanently in position in the ground. The lower part of the post is provided with a cap D having an outwardly extending flange *a* formed thereon. A similar cap E is fitted on the lower end of the upper part B of the post and this cap E is also provided with a flange *b* similar to the flange *a*.

In the end of one part of the post is fitted a pin F extending through the cap and into the post. This pin is adapted to fit into a socket *c* formed in the end of the other part of the post.

The cap E has an annular rib *d* formed therein the purpose of which will herein-after appear.

The construction described allows the post to be separated into two parts for convenience and transportation. The flanges *a* and *b* when the parts are connected serve to give a broad bearing to steady the parts

and hold them in alinement without undue strain upon the pin F.

On the part B of the post a collar G is adapted to slide. On this collar are suitably pivoted the inner ends of the arms H. At the upper end of the post is a guide cap I provided with arms J having guide slots *e* formed therein through which the arms H pass. This guide cap is rotatably mounted on the post in any suitable manner and preferably as follows: The post is provided with a metal cap K and a vertical rod or tube L forming an upward extension of the post passes through the guide cap I, the cap K and into the end of the upper part B of the post.

From the construction above described it follows that by sliding the collar G on the post that the arms may be caused to assume either the position shown in Fig. 1 or the position shown in Fig. 2 at will, the arms sliding freely through the slots in the guide cap I.

To suitably brace the arms and to aid in folding the same I provide the following mechanism: On the rod L a collar M is slidably mounted. Braces are pivotally connected at their inner ends to this collar and at their outer ends to the arms H. When the arms are extended the collar is preferably in such a position that the braces are somewhat lower at their inner ends than their outer, so that they not only will resist the strain caused by any weight of clothes supported by the arms but will also resist any upward strain tending to fold up the arms.

The lower limit of movement of the collar M is set by means of a sleeve *f* encircling the rod L and formed integral with the guide cap I and which forms a shoulder at its upper end against which the collar M may abut.

The collar M when raised will cause the arms H to fold together. To aid in raising the collar I preferably secure to the upper ends of the rod L a sheave *o* over which passes a cord *g* secured at one end of the collar M having its other end hanging down within reach of the user. By drawing on this cord the collar M may be raised and the device folded into the position shown in Fig. 2 with very little trouble.

The upper part of the post with the folded arms may then be lifted off and carried away for storage. The lower part of the post may also be lifted out and carried away if desired.

The whole device it will be noted stows very compactly the end of the rod L projecting little, if any, beyond the ends of the arms H while the collar G abuts on the cap E.

The device is releasably held in its folded position by means of a spring latch engaging the rib d and the collar G may also be held in its raised position until the arms have assumed their extended position by means of a spring catch engaging the guide cap I. While any suitable devices might be employed for the purposes described I show a two-ended spring catch P the lower end of which is adapted to snap over and engage the upper edge of the guide cap I. I do not, of course, desire to restrict myself to the precise construction of this spring catch and it is merely shown in its simplest form.

I prefer to connect the ends of the pairs

of arms J of the guide cap to form a complete ring Q which prevents the lines for the clothes catching on the arms J but this construction is not essential.

30

From the above description it is evident that I have devised a clothes drier which is easily opened out or folded and which is securely held either from accidental folding when open or from partial opening out when folded.

35

What I claim as my invention is:

In a clothes drier the combination of a post; a collar vertically slidable thereon; arms pivoted at their inner ends on said collar; a cap having guide slots therein through which said arms pass and in which they may move from a substantially vertical to an outwardly directed position; an upper collar vertically slidable on the post; and braces pivotally connected to the arms and to the upper collar.

40

Hamilton this 4th day of Nov'r, 1909.

WILLIAM L. CUMMER.

Signed in the presence of—

L. COLEMAN,
HAROLD H. CUMMER.
